UNITED STATES PATENT OFFICE.

ROBERT PATTERSON GASTON, OF BALTIMORE, MARYLAND.

CARD-RACK.

1,309,194.

Specification of Letters Patent.

Patented July 8, 1919.

Application filed October 4, 1917. Serial No. 194,823.

To all whom it may concern:

Be it known that I, ROBERT PATTERSON GASTON, a citizen of the United States, residing at Baltimore, in the State of Maryland, have invented certain new and useful Improvements in Card-Racks; and I do hereby declare the following to be a full, clear, and exact description of the invention, such as will enable others skilled in the art 10 to which it appertains to make and use the same.

My invention relates to card racks.

One object of my invention is to provide a rack having a plurality of sections in 15 which each section shall be so disposed with reference to the other sections and so designated by indicia attached thereto that it may be used for the temporary reception of cards, when said cards are to be segregated 20 from a heterogeneous collection of cards and arranged according to any predetermined system.

A further object of my invention is to provide a rack for accomplishing the afore- 25 said purpose which shall be simple, cheap and capable of facilitating the segregating operation.

A further object of my invention is to provide a rack which shall be capable of quickly 30 reversing the position of the cards therein at the end of each segregating operation.

A further object of my invention is to provide a frame for removably supporting said rack so that the rack and coöperating 35 parts may be removed from the frame during the periods when the segregating operation is not to be performed, thus permitting the frame to be used as a table.

These and further objects of my invention 40 are obtained by the use of the instrumentalities illustrated in the accompanying drawings, in which:

Figure 1 is a front view of my improved card rack and supporting frame, portions 45 thereof being broken away, the covers being in place.

Fig. 2 is a view of the parts shown in Fig. 1 looking in the direction of the arrow 2.

Fig. 3 is a view of the top of the parts 50 shown in Fig. 1 looking in the direction of the arrow 3.

Fig. 4 is a detail view of the lock for locking the card rack in position.

Fig. 5 is a view of the parts shown in

Fig. 4 looking in the direction of the arrow 5.

Fig. 6 is a section along the line 6—6 of Fig. 1 looking in the direction of the arrow.

Fig. 7 is a front view of my improved card rack, the covers being removed.

Fig. 8 is a view of one form of card for which my improved card rack is adapted.

Fig. 9 is a section along the line 9—9 of Fig. 7 looking in the direction of the arrow, 65 but the covers are shown in place.

Fig. 10 is a perspective view of a stop gap for use with my improved card rack, as hereinafter explained.

In the drawings:

15 represents a frame consisting of the side pieces 16—16 supporting the table 17, said parts being secured together in any approved manner and additional strength being secured by means of the brace 18.

The side pieces 16—16 are shaped in profile as shown in Fig. 2, and are provided at their tops with slots 19—19. The parts just described may be formed of wood, metal or any suitable composition and joined together in any suitable manner.

The shaft 20 is provided with smooth portions 21—21 which are revolvably mounted in the slots 19—19. The ends of the shaft 20 are provided with threaded portions upon 85 which are screwed the nuts 22—22 and said shaft is also provided with enlarged threaded portions 23—23, upon which are screwed the flanges 24—24. The adjacent faces of the nuts 22—22 and flanges 24—24 are so 90 located as to loosely embrace the upper ends of the said pieces 16—16.

Between the inner faces of the flanges 24—24 there is mounted my improved card rack 25, which consists of a bottom, 26, a top 27, a left hand side piece 28 and a right hand side piece 29. The side pieces 28 and 29 are secured to the flanges 24—24 in any approved manner such as by screws 30, shown in Fig. 7. The shaft 20 is provided 100 with a portion 31 which extends between the flanges 24—24, and all parts of said shaft are formed integrally.

The center shelf of my improved card rack is formed by the two portions 32—32 105 (see Fig. 9), the inner edges of said portions being close to the shaft portion 31, and said portions 32—32 extend from the

side 28 to the side 29 and are secured thereto in any approved manner. The thickness of the portitons 32—32 is equal to, or greater than, the diameter of the shaft portion 31.

The top intermediate shelf 33 and the bottom intermediate shelf 34 are substantially equal in thickness to the thickness of the center shelf sections 32 and said bottom and top intermediate shelves extend between the sides 28 and 29. A plurality of vertical dividing pieces 35 is secured between the bottom 26 and the top 27. Any desired number of vertical pieces 35 may be used. The number that it is necessary to use in a rack for segregating any particular set of cards will depend upon the number of different indicia that may exist upon said cards.

For instance, my improved rack shown in the accompanying drawings is provided with nine vertical dividing pieces 35, making ten compartments 36, thus rendering it suitable for use with cards such as shown in Fig. 8, upon which there exists a plurality of vertical series of numbers from 0 to 9. It is evident that there may be as many compartments 36 in addition provided as may be desired, whether same are to be used or not, but the minimum number of compartments required is that number which will be equal, as above stated, to the number of different indicia upon the cards which are to be segregated.

Whatsoever number of compartments 36 is provided between the bottom 26 and the bottom intermediate shelf 34, there is provided a like number of compartments such as 40 above the compartments 36, a like number of compartments such as 41 above the compartments 40 and a like number of compartments such as 42 above the compartments 41.

It is to be noted that the dividing pieces 35 are each provided with a hole which fits tightly upon the portion 31 of the shaft 20, hence the shaft supports each dividing piece and thus greatly stiffens the card rack.

A handle 43 is secured in any approved manner to the bottom 26 and a similar handle 44 is similarly secured to the top 27.

The outer edges of the bottom 26, the top 27, the shelf portions 32—32 and the shelves 33 and 34 are provided with a plurality of finger holes 47—47, there being one finger hole on each of said edges for each of the compartments 36, 40, 41 and 42, and said finger holes are located near the center of said compartments so as to provide easy access for the fingers to the edges of the cards when same are to be removed, as hereinafter explained.

In order to provide means for locking the card rack 25 in a vertical position, circular segments 48—48 are secured in any ap-

proved manner to the bottom 26 and top 27 near the center thereof. These segments extend slightly beyond the outer edges of the bottom 26 and top 27, as shown with reference to the bottom 26 in Fig. 5, so as to provide supports for the covers 49 and 50. Each of the circular segments 48—48 is provided with a notch 51 for the reception of the stopping piece 52.

The center portion of the stopping piece 52 is adapted to fit loosely within the notch 51 and said stopping piece is provided with two ends 53—53 which are somewhat thinner than the center portion thereof. Said ends are adapted to slide freely within the U shaped guides 54—54, the latter having feet 55—55 which are secured to the base 56 in any approved manner. The base 56 is secured to the table 17 by wing screws such as 57—57, the latter passing through the base 56 and having a threaded portion screwed into holes in the table 17.

In order to keep the stopping piece 52 in the position shown in Figs. 4 and 5, the springs 58—58 are provided, the ends of 90 said springs resting in holes provided in the stopping piece 52 and the base 56.

The covers 49 and 50 are made of such sizes that their edges will be flush with the outer surfaces of the bottom 26, the top 27, 95 the left side 28 and the right side 29, and the lower and upper edges of said covers will thus fit loosely between the inner faces of the circular segments 48—48.

The covers 49 and 50 are further secured 100 in place by the metallic fingers 59—59 and 60—60, the former being secured, respectively, at the bottom and the latter at the top of the side 28, as shown in Fig. 1, in any approved manner such as by screws 61, 105 and the finger portions thereof extend over the outer faces, of the covers 49 and 50.

The covers 49 and 50 are provided on the edges adjacent to the side 29 with metallic locking pieces 62—62, the latter being secured to the covers 49 and 50 by screws such as 63.

Spring pressed catches 64—64 are located so that their inwardly disposed end may co-act with the locking piece 62 in order to 115 secure the covers 49 and 50 in position. The catches 64—64 are revolvably mounted upon the pin 65 and the latter is rigidly secured in the ear 66 which is formed integrally with the base 67 and the bases 67 are secured 120 to the side 29 by screws such as 68, shown in Fig. 6. The catch 64 is provided with a handle 69 and a spring 70 located between said handle and the base 67 serves to normally keep the catch 64 in contact with the 125 locking piece 62, as shown in Fig. 6. In order to provide clearance around the catch 64 and the base 67, slots such as 71, shown in Fig. 6, are provided in the covers 49 and 50.

The stop gap 72 shown in Fig. 10 is provided for a purpose hereinafter explained. It consists of two flat portions 73—73 which may be of wood, metal or other suitable composition and they are joined together by two cylindrical posts 74—74, the latter being secured in any approved manner in the flat portions 73—73.

The rack and stop gap just described may 10 be used with the form of card shown in Fig. 8 on the face of which there is printed at the top the words "Invoice No." and "State No." Below the words "Invoice No." there are printed six vertical columns, each column 15 containing the numbers from 0 to 9, inclusive, and a vertical dotted line being printed between the third and fourth vertical rows of numbers. At the right of the last vertical row of said figures, there is 20 printed a vertical solid line which divides the vertical rows of invoice numbers from the vertical rows of State numbers. The State numbers consist of two vertical rows of numbers from 0 to 9 printed to the right 25 of said solid vertical line and under the heading of "State No."

The operation of my improved card rack is as follows:—

It will be assumed that there are a plurality of cards, (similar to the card illustrated in Fig. 8), which are either delivered to the operator without regard to any particular order or which are stacked or lying heterogeneously. It will also be assumed 35 that said cards are to be assorted and stacked so that the numbers under "Invoice No. —" will be in proper numerical order.

It is to be noted by an inspection of Fig. 8 that the zeros under "Invoice No. —" occupying the thousands place have been punched out and that the 1 in the hundreds place, the 2 in the tens place and the 4 in the units place have also been punched out and said punching causes the number of 45 the card shown in Fig. 8 under the heading "Invoice No. —" to be 124.

It will also be noticed that the 3 in the tens place and the 4 in the units place under "State No. —" have also been punched out, 50 thus causing the card shown in Fig. 8 to be number 34 under "State No. —."

There may be any number of headings at the top of a card for any number of classifications and there may be as many vertical 55 rows of figures or other indicia as there are subjects to be classified under that heading.

It will be assumed that the cards are to be 60 assorted and stacked according to their invoice numbers and it will be further assumed that the operator picks up first the card shown in Fig. 8 and it will be further assumed that the front cover 49 is removed from the rack and that the rear cover 50 is in place thereon.

65 The operator then takes the card shown

in Fig. 8 and notices that the digit which is punched out in the units place is No. 4. He then places said card, face downward, in the bottom section of the row of sections marked 4 in full lines on shelf 33, (see Fig. 7). 70 The operator then continues to place the remainder of the cards, face downward, in the bottom section of that row of vertical sections for which the number shown full on the shelf 33 in Fig. 7 corresponds to the 75 number punched out in the units place under "Invoice No. —."

When any of the bottom sections become full of cards, the operator continues to pile the cards numbered corresponding to that 80 section in the sections above.

It is to be noted that all the sections in each vertical row of sections are designated by the number shown by full lines on the shelf 33. 85

It is evident that when the cards are segregated as just described, each card will be lying face downward in a section in one of the vertical rows of sections that is numbered in full lines on shelf 33 to correspond with 90 the number punched out in the units place under the caption "Invoice No. —." Consequently, the card shown in Fig. 8 will be lying face downward in the section of the vertical row of sections that is numbered 4 95 on shelf 33.

The left edge of the front cover 49 is then placed under the fingers 60 and 60 and between the inside faces of the circular segments 48 and the right hand edge is pressed 100 inwardly until the locking pieces 62 are under the catches 64. The operator then presses down the stopping piece 52 until the same is out of the notch 51. He then grasps the handle 44 and turns the card rack 105 25 upside down until the notch similar to 51 in the top circular segment 48 embraces the stopping piece 52.

While the operator is turning the card rack upside down it is unnecessary that he 110 retain hold upon the stopping piece 52. It is only necessary that he press said stopping piece down during the initial stage of the turning movement. As the card rack is turned around, as just described, the outer 115 face of the top circular segment 48 will strike the stopping piece 52 and depress it until the slot similar to 51 is opposite said stopping piece and then the springs 58 will force the stopping piece into said slot. 120

The rear cover 50, which is now at the front, is to be removed and all the cards are now lying face up and the numbers shown dotted on shelf 34 in Fig. 7 now show on the front and will read the same as the numbers 125 shown by full lines, read in Fig. 7.

It is also evident that the cards which before occupied the bottom section are now at the top and that the lower sections are unoccupied.

In case there is a sufficient number of cards to completely fill any of the vertical rows of sections of the card rack during the first segregation, it is necessary that a second 5 card rack be used to perform the second segregation about to be described or that the cards be removed from the bottom section.

The operator now takes the top card out of the top compartment in the zero vertical 10 row of sections and he places said card face downward in the bottom section in the vertical row of sections that is numbered on shelf 34 in dotted lines corresponding to the figure punched out in the tens place under the caption "Invoice No. —."

The operator continues this operation on all the cards in the zero section until all the cards in said section have been segregated according to the numbers punched out in 15 the tens place.

It will thus be evident that the cards in any section will be those in which the number punched out in the tens place corresponds to the number shown dotted on shelf 20 34 which designates the vertical row comprising said section.

Since this collection of cards during the first segregation has been segregated so that it comprises only cards having zero in the 25 units place, it is evident that the zero row of sections will now contain nothing but cards having zero in the units and tens places; the sections in the row of sections marked 1 will contain nothing but cards having zero punched out in the units place and ones punched out in the tens place; the section in the row of sections marked 2 will contain nothing but cards having zero punched out in the units place and 2 punched out in the 30 tens place, and so on for the rest of the sections.

The operator then similarly segregates all the cards occupying the sections in the vertical rows marked 1, 2, 3 and so on, and thus 45 it will be evident that the section in each vertical row of sections will contain the cards having punched out in the tens place the number which corresponds to the number which designates said vertical row and 50 is shown dotted on shelf 34. It is also evident that the cards lying face downward at the bottom of the bottom compartment in each row will be the cards having zero in the units place, the cards next superimposed 55 will be the cards having one in the units place, and superimposed above the cards having one in the units place will be the cards having 2 in the units place, and so on.

The cover 50 is now put on in the same 60 manner as was described with reference to the cover 49 and the rack is turned upside down as before described, excepting that the operator uses the handle 43 which is now at the top. The front cover 49 is now removed and the cards are again face up.

Should any of the vertical rows of sections be completely filled up during the segregation just described, a second rack is to be used or some of the cards are to be removed from the bottom section, as before 70 explained.

The operator now takes the top card out of the top section in the zero row of sections and places it face downward in the bottom section in the vertical row of sections 75 designated by the number shown in full lines on shelf 33 which corresponds to the number punched out in its hundreds place.

Then the operator continues this operation on all the cards in the zero section until 80 all the cards in said section have been segregated according to the numbers punched out in the hundreds place.

It will thus be evident that the cards in any section will be those in which the number punched out in the hundreds place corresponds to the number shown by full lines 85 on shelf 33 which designates the vertical row comprising said section. Since this collection of cards during the first and second 90 segregations has been segregated so that it comprises only cards having zero in the units and tens places, it will be evident that the zero row of sections will now contain nothing but cards having zero in the units, 95 tens and hundreds places; the sections in the row of sections marked 1 will contain nothing but cards having zero punched out in the units and tens places and ones punched out in the hundreds place; the section in the 100 row of sections marked 2 will contain nothing but cards having zero punched out in the units and tens places and 2 punched out in the hundreds place, and so on for the rest of the compartments.

The operator then similarly segregates all the cards occupying the sections in the vertical rows marked 1, 2, 3 and so on, and thus 110 it will be evident that the section in each vertical row of sections will contain the cards having punched out in the hundreds place the number which corresponds to the number which designates said vertical row and is shown dotted on shelf 34. It is also evident that the cards lying face downward at the bottom of the bottom section in each row will be the cards having zero in the units and tens places; the cards next superimposed 115 will be the cards having zero in the tens place and one in the units place and superimposed above the cards having zero in the tens place and one in the units place will be the cards having zero in the tens place and 2 in the units place, and so on.

The cover 49 is then placed in position in 125 the same manner as already described and the segregation continues in the same order for the numbers in the thousands, tens of thousands, hundreds of thousands and so on, places,—the net result of the operations be- 130

ing that the cards will be finally stacked and lying in correct numerical order. Thus, the card shown in Fig. 8 will be lying in between the cards punched 123 and 125.

5 If the segregation is to be made according to State numbers or according to any other indicia that may be put upon the card, the procedure is exactly the same as has been described with reference to the numerical 10 indicia.

I claim:—

1. The combination with a card rack comprising a plurality of sections open at both ends, of a frame for revolubly supporting said rack, removable covers for said ends revolving with said rack, notches on said rack and a stopping piece supported by said frame and located to enter any one of said notches to stop said frame in the position 20 corresponding to said notch.

2. The combination with a card rack, of a frame for revolubly supporting said rack, a plurality of circular segments secured to said rack, a notch in each segment, a stopping piece supported by said frame and located in the path of said circular segments, guides for said stopping piece supported by said frame and springs for forcing said stopping piece into said notches.

3. The combination with a card rack, of a frame for removably and revolubly supporting said rack, a table supported by said frame beneath said rack, notches on said

rack and a spring pressed stopping piece removably supported on said table located 35 to enter said notches.

4. The combination with a card rack comprising a plurality of sections open at both ends, of means for revolubly supporting said rack, removable covers for said 40 ends revolving with said rack, means for locking said rack in two positions, and an index upon each end of each section, the indicia for each section being similar, whereby the sections are similarly indexed in each 45 position of said rack.

5. The combination with a card rack comprising a plurality of sections open at both ends, of means for revolubly supporting said rack, removable covers for said ends revolving with said rack, means for locking said 50 rack in two positions, and an index upon each end of each section, the indicia for each section being dissimilar and the indicia for said ends being arranged according to the same order from left to right when viewed from either side of said rack.

6. A card rack comprising a plurality of sections open at both ends in combination with covers therefor, means for supporting 60 said covers at the bottom thereof, fingers for retaining one edge of each cover and locking pieces and catches for retaining the other edge thereof.

In testimony whereof I affix my signature. 65
ROBERT PATTERSON GASTON.

Copies of this patent may be obtained for five cents each, by addressing the "Commissioner of Patents, Washington, D. C."
